CLARENCE P. BRONSON, OF CORNING, NEW YORK, ASSIGNOR OF ONE-FOURTH TO
KURTZ E. GRISWOLD AND ONE-FOURTH TO HERBERT L. GRISWOLD.

SOCKET-WRENCH

1,034,383.

Specification of Letters Patent. Patented July 30, 1912.

Application filed April 7, 1911. Serial No. 619,626.

To all whom it may concern:

Be it known that I, CLARENCE P. BRONSON, a citizen of the United States, residing at Corning, in the county of Steuben and State of New York, have invented certain new and useful Improvements in Socket-Wrenches, of which the following is a specification.

My invention relates to socket wrenches such as are ordinarily used in connection with automobiles and gasoline engines and similar contrivances.

The object of my invention is to provide a combination of socket wrenches or a nest of socket wrenches which are adapted to fit a number of bolts or nuts of different sizes, the smaller sizes of which wrenches are nested within the larger sizes progressively, the largest size being fastened to a stem.

A further object of my invention is to provide a handle for said stem that can be folded up into line with said stem and positively held there while said handle is being used as a flat wrench, for which the stem and socket wrench then becomes the handle, the handle having the shape of a flat wrench, being provided at each end with the jaws thereof and with recesses intermediate of said ends.

A further object of my invention is to permit the handle being extended transversely to the stem so as to provide a sufficient leverage for turning said wrench, and a nut in engagement therewith.

Further objects of my invention will appear in the specification and drawings, the novel features thereof being properly pointed out in the claims at the end thereof, it being understood that various changes in the form, proportion and minor details of construction may be resorted to without departing from the spirit or sacrificing any of the advantages of this invention.

In the accompanying drawings, Figure 1 is a side elevation of my wrench with one of the inner socket sections thereof extended, the handle being shown in full lines in its transverse position for operating the socket wrench, and in dotted lines in its ex-

tended position for use as a flat wrench. Fig. 2 is a section on the line 2^x—2^x in Fig. 1, the handle being shown in full lines. Figs. 3 and 4 are views of bushings intended to be used with one of the sockets for the purpose of taking up the clearance between it and a nut which is to be turned thereby. Fig. 5 shows a modification of the handle and stem of the socket wrench, showing a construction by which the leverage on the socket wrench may be increased. Fig. 6 is a side elevation of the part shown in Fig. 5. Fig. 7 is a detail view of the parts shown in Fig. 6 with the handle turned down to horizontal position. Fig. 8 is a side view of the parts shown in Fig. 7.

In the accompanying drawings like reference characters refer to like parts.

My improved wrench consists of a main body portion or socket 1 which is preferably of hexagonal shape, although the number of sides on the socket constitutes no necessary part of my invention. This main body portion has a cone shaped end 2 to which is attached a stem 3, this stem being integrally attached thereto, as shown in Figs. 1 and 2, and pivoted thereon as shown in Figs. 5, 6, 7 and 8, for a purpose which will presently be described. The stem 3 is slotted at 4, as is indicated in cross section in Fig. 2, and in such slot at the end is provided a screw or pin 5 having a head 6 on one end thereof, the other end thereof being threaded and being provided with a thumb nut 7. On this pin 5 the handle 8 is mounted, the handle being slotted at 9 so as to permit longitudinal adjustment thereof on the pin 5. The handle may be set in the position shown in Fig. 1, in which position it may be clamped by the thumb nut 7, or it may be slid either to the right or to the left and used in such position to turn the socket wrench. The handle is provided with the alligator jaw 10 at one end and with the square opening 11 adjacent thereto, and is provided at the other end with the hexagonal opening 11 and the forked opening 12. The handle with either of these openings may be used as a flat wrench, either sepa-

rately from the main body portion of the wrench or in connection therewith. When used as a flat wrench the main body portion of the wrench can be used as a handle therefor, materially increasing the leverage thereof, and the construction by which this result is secured I will now describe.

At the bottom of the slot 4 I provide a lug 14, with which either the opening 10 or 10 the opening 12 at the ends of the handle is adapted to engage. For this purpose the handle may be rotated to the dotted line position shown in Fig. 1 and moved endwise so that the inner end of the handle 15 engages with said lug, whereupon it may be clamped in that position by means of the thumb nut 7. While in that position the wrench as a whole may be applied to a nut, for example 15, and the socket or body portion 20 of the wrench may then be used as a handle for the purpose of turning such nut by the wrench.

Carried on the main body portion of the socket wrench is the spring 16 having a pin 25 17 mounted thereon, which pin passes through the perforations 18 in the various sections of the socket wrench. It will be understood from an inspection of Fig. 2 that the main body portion or the outer socket is 30 rigid with the handle or stem, and that nested within such socket is shown three other sockets progressively reduced in size so that the one fits snugly within the other. Each of these sockets is perforated at two 35 places with the holes 18, so that each of said sockets in turn may be moved to either the inner or the outer position, in either of which positions it can be held by the pin 17. It will thus be seen that the particular 40 socket which is of the same size as the nut which is to be turned can be moved to the extended position and fastened in such position, and can be used accordingly, or the inner sockets may be removed, in which case 45 the socket that is of the proper size for use can be used in its innermost position for the purpose of turning the nut. In case the socket does not make a close fit, a bushing 19, such as is shown in detail in Figs. 3 and 50 4 and in position in the extended socket in Fig. 2, may be inserted in said socket for the purpose of taking up the extra space between such socket and the nut to be turned. These bushings are preferably of flat metal 55 made U-shaped, with the ends turned out, and are intended to fit the socket closely and are of sufficient thickness to take up the clearance between the socket and the nut. It will be understood that one side of the bushing 60 19 may be omitted if desired.

It will be seen that a number of sections or sockets may be provided, each of which in turn may be thrown to operative position and held firmly in said operative position

while it is being used, and when it is desired to change one section for another the pin 17 may be quickly moved out to permit the readjustment of the inner section, after which they may be again locked in their readjusted position.

In Figs. 5, 6, 7 and 8 I have shown a modification of my improved wrench. In this form the body portion 1 terminates in a reduced end 20, and the handle or stem 3 terminates in the forked end 21 which is pivoted on said reduced end by means of the pin 22. The reduced end 20 has a vertical slot therein as indicated at 23, which permits a slight movement of the handle up and down thereon, the pin 22 being permitted to move up and down by the length of the slot minus the diameter of the pin. This permits the handle to be turned down to the position shown in Fig. 8, thus increasing the leverage of the handle on the 80 socket. The handle 8 can engage with the stem 2 in the same way as it engages with it in the construction heretofore described, the stem 3 being in each case provided with the lug 4 with which the handle can engage. 90 It will also be understood that the reduced end 20 has its ends narrowed at the top, as shown at 24, and the stem 3 has a recess therein corresponding therewith to fit on said projection 24, into and out of engagement with which it can be moved by a longitudinal movement of the stem when the parts are in the position shown in Figs. 5 and 6.

It will thus be seen that my improved 100 wrench is capable of use in a great variety of ways, all of which uses are secured by the construction heretofore described.

Having thus described my invention, what I claim as new and patentable is as follows:

1. In a wrench the combination of a main body portion having a socket therein, a series of graduated sockets nested therein, a perforation through the outer socket, a series of perforations in line therewith 110 in each of the inner sockets, said inner sockets each being separately movable to an inner or outer position, and a pin passing through the perforation in the outer section and engaging with one of the perforations in each of said inner sockets to hold each of said inner sockets in its inner or outer position, said sockets being separately or collectively removable from said main body portion on the withdrawal of said 120 pin, a spring or other flexible mounting attached to the socket on the main body portion for supporting said pin and yieldingly holding it in place.

2. The combination in a tool, of a handle 125 having a slot therein open at one end, a pin in the outer end of said handle across said slot, a lug projecting across said slot at the

end thereof opposite said outer end, a pivoted slotted member mounted on said pin, said member having at its opposite ends, open ended heads, said pivoted slotted member being capable of being swung about said pin, into alinement with said handle and moved lengthwise to engage one of its open ended heads with said lug to permit the

other open ended head to be used as a tool with the rest of the tool as a handle therefor. 10

In testimony whereof I affix my signature in presence of two witnesses.

CLARENCE P. BRONSON.
